UNITED STATES PATENT OFFICE

FRANK A. TOPPING, OF GRAND RAPIDS, MICHIGAN, ASSIGNOR TO JOHN M. SWEENEY,
OF GRAND RAPIDS, MICHIGAN

DESIGN FOR A COMBINED CORK PULLER AND BOTTLE OPENER

Application filed July 29, 1929. Serial No. 32,240. Term of patent 7 years.

To all whom it may concern:

Be it known that I, FRANK A. TOPPING, a citizen of the United States, residing at Holmdene Blvd., N. E., Grand Rapids, in the county of Kent and State of Michigan, have invented a new, original, and ornamental Design for Combined Cork Puller and Bottle Opener, of which the following is a specification, reference being had to the accompanying drawings, forming a part thereof, in which:—

Figure 1 is a front elevational view of the combined cork puller and bottle opener showing my new design; and

Figure 2 is a side elevational view thereof.

I claim:

The ornamental design for a combined cork puller and bottle opener, substantially as shown.

FRANK A. TOPPING.
